TIMER FOR WEFT DETECTORS OF BOX LOOMS

Application filed March 22, 1932. Serial No. 600,470.

This invention relates to improvements in weft detecting mechanisms for box looms and it is the general object of the invention to provide improved means for delaying the actuation of loom change mechanism in those looms where the detecting circuit may be closed as soon as a previously active shuttle is shifted to inactive position.

In my co-pending application Serial No. 593,814 I have shown detector mechanism using an electric circuit closed as soon as a depleted shuttle becomes inactive operating in conjunction with mechanically timed and operated devices for delaying the stopping of a loom until the indicating shuttle is again active and either at or on its way toward the magazine end of the loom. In that application the knock-off or actuator is effective by its position and the time of its working stroke to prevent loom stoppage as soon as the detecting circuit is closed, there being a cam or the like which determines the movements of the actuator.

In certain types of looms, especially those weaving fine grades of cloth, it is desirable to prevent the lay from beating the fell of the cloth when the filling is defective, and in some instances operators prefer to stop the loom in time to prevent a second beat of the reed against a pick of filling. To accomplish this result the brake is frequently set to stop the loom quickly.

In the so-called Stafford type of shuttle changer loom the lay is brought to rest to effect change of shuttles, the brake mechanism of course being employed to stop the lay in proper position for the change. Since the brake acts quickly for reasons other than those attending shuttle change, and, further since it is desirable to stop the lay at back center, the knock-off must start its working stroke late, so late in fact, that the detector circuit will already have been closed, thus causing the loom to stop two picks too soon.

It is an important object of my present invention to render the timing of the knock-off or actuator working stroke independent of the closure of the detecting circuit, the purpose of this relation being to permit the actuator to be timed most favorably with

respect to the brake mechanism of the particular loom to which the detecting mechanism is applied. Accordingly, I provide two open points in the detecting circuit one of which is to be closed at indication of weft exhaustion by a weft feeler contacting with a depleted inactive shuttle, and the other point being closed periodically and sufficiently late in the cycle of the loom to avoid premature stopping of the loom. By the use of mechanism as set forth herein the weaver is free to adjust the stopping of the loom due to warp breakage, for instance, without interfering with the correct operation of the shuttle changer devices.

While the invention has been set forth in connection with a loom which stops at transfer, yet it is equally useful in those looms where transfer of a bobbin or changing of a shuttle takes place while the loom is running, the knock-off in such looms being replaced by an actuator which effects the change. In either type of loom the desirable feature of being able to adjust the closing of the circuit and the beginning of the changing structure independently of each other is retained.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a side elevation of a portion of a loom provided with my invention,

Fig. 2 is a diagrammatic view of the electric circuits employed in my invention,

Fig. 3 is a front elevation of the end of the loom having my detecting mechanism,

Figs. 4, 5 and 6 are diagrammatic views of the operating parts in different positions, and

Fig. 7 is a time diagram showing the timing of the various motions in relation to the crank shaft.

Referring to the drawings, the loom frame 10, breast beam 11, crank shaft 12, bottom shaft 13, operating at half the speed of the crank shaft, lay sword 14 and lay 15 are

of usual construction. Shifting shuttle boxes 16 having upper and lower cells 17 and 18, respectively, receive shuttles 19 and 20, respectively, carrying bobbins 21. The top 5 and bottom bobbins have electric contact ferrules 22 and 23, respectively. The shifting shuttle box is moved up and down to present each shuttle to active position for two picks only at a time, by any suitable well-known 10 mechanism including a box lever 24 and lifter rod 25.

I have illustrated a type of feeler mechanism capable of closing an electric circuit. The lay end 26 has an upper horn 27 supporting a top feeler 28 formed of insulating material and guiding two sliding insulated electric contact spring plunger needles 29. In similar manner, a lower detector 30 has contact needles 31 to engage the lower bobbin 20 ferrule 23.

Shifting of the shuttle boxes will ordinarily start when the lay is on bottom center, or when the active shuttle is completely boxed on the left end as viewed in Fig. 3. The 25 shifting continues until top center, or the time for picking. The shuttle which is being moved to inactive position is therefore presented to its feeler, usually shortly after front center. The time of contact between 30 the needle plungers and the ferrule can be delayed somewhat, but the detector will not ordinarily be permitted to interfere with the proper timing and action of the shuttle boxes. As a matter of fact, contact can be 35 established any time during the latter part of the box shifting motion, or after front center. If weft be absent in any shuttle moving to inactive position, the corresponding feeler will have its needles electrically connected by the exposed ferrule.

A shipper handle 35 is positioned to strike a switch arm 36 of a switch 37 to open a circuit through the switch when the handle is in non-running position. An electro-magnetic device 38 is mounted on fixed structure and controls a latch 39 pivoted to a control lever 40. The rear notched end of the latch is movable from normal low position up into the path of movement of a regularly moving 45 actuator 41. The latter is moved back and forth and is set to stop the loom and apply the brake at the proper time to arrest the lay in rear position. By means described in my co-pending application Serial No. 593- 55 814 movement of the latch to the right in Fig. 1 will set the brake 42 and throw the shipper lever 43 to stop the loom.

The mechanism thus far described is not claimed herein as it forms part of the subject-matter of my prior application above identified, in which prior application this subject-matter is claimed and to which application reference is made for a more complete and detailed description thereof. As 60 65 previously stated, the important object of

my present invention is to render the timing of the knock-off actuating mechanism independent of the time of closing the detector circuit which was not the case in my prior application.

In order that the setting of the actuator may be independent of the feeler, I provide a second switch located and actuated so as to permit closure of the detector circuit only after the latest permissible time for operating the actuator. In this way all likelihood of premature indication is avoided.

In carrying out this part of my invention I provide the bottom shaft 13 with a cam 50 electrically insulated from the rest of the loom and completing a rotation every second pick of the loom. A flexible switch plate 51 lies in the path of the cam and engages the latter electrically at a predetermined time in the loom cycle, this time being variable by adjusting the cam angularly on the shaft. The cam should engage the plate 51 some time prior to shifting of the boxes. The cam 52 on the bottom shaft, which moves the actuator, is also adjustable angularly to time the setting of the brake as desired.

In addition to the shipper handle switch which is closed constantly during loom operation, there are therefore two switches which must be closed to initiate a change in loom 55 operation, one at the detector mechanism, and one independent of the detector and closed periodically by loom operation. This last switch is in series with the detector mechanism, and therefore controls the detector 100 circuits.

Assuming that the top shuttle is depleted and being moved to inactive position, the top feeler needles will contact with ferrule 22 and close the top feeler contact or switch. As 105 stated, this may occur before the actuator 41 starts its forward working stroke. Cam 52 then gives the actuator its working stroke, at a time in the loom cycle determined by the brake. After the latest time when the actuator could operate and effect lay stoppage in correct position for shuttle change, the cam 50 will engage the contact plate 51. Thereupon, the following circuit will be closed: 110 Ground, wire 60, left top feeler needle, ferrule 22, right needle, wire 61, cam 50, plate 51, wire 62, wire 63, electro-magnetic device 38, wire 64, switch 37, wire 64, battery 65, and wire 66 back to the ground. This energizes the device 38 the effect of which is to 115 raise latch 39. This occurs when the actuator is in the dotted line position in Fig. 4.

On the non-working stroke the actuator will return to the full line position shown in Fig. 5, with cam 52 pointed to the right. It 125 may dwell in this position for a pick, or until the cam 52 reaches the position shown in Fig. 6. The second working stroke of the actuator causes engagement of the latch and moves the parts to the dotted line position 130

shown in Fig. 6. The result of this last action is to rock the knock-off lever 40, whereupon a change occurs, such as described in my aforesaid application.

5 Should exhaustion occur in the bottom shuttle, the circuit traced will be the same, except that the lower needles and wires 70 and 71 are in circuit instead of the corresponding parts associated with the other 10 circuit.

The cam 50 closes the circuit sufficiently long prior to breaking at the shuttle to permit operation of the devices. The timing of the cam 50 can be set to accommodate the 15 actuator, holding the latch raised until the actuator engages it. If desired, however, a shunt circuit may be used to hold the electro-magnetic device energized until the shipper handle breaks the circuit at switch 20 37. This shunt circuit includes wire 75, lever 76 which lifts the latch, core of the magnet 77 which has metallic contact with the lever, wire 78, and ground. Engagement of lever 76 with the core 77 will close the following 25 circuit: Battery 65, wire 64, switch 37, wire 64, device 38, wire 63, wire 75, lever 76, core 77, wire 78 to ground, and up from the ground over wire 66 back to the battery. Current 30 in this circuit will maintain the device 38 energized regardless of the condition of the detector switches, or the cam operated switch at plate 51.

It is to be understood that the timing of the several control elements or members is 35 such that although the detector switch is closed as soon as, or even before, an exhausted shuttle is shifted to inactive position, yet the actuator will have passed beyond the notch in the latch 39 before cam 50 closes 40 the circuit at the contact plate. On the pick when the empty shuttle is moved to inaction, therefore, the lever 40 cannot be rocked, this result occurring on the second pick thereafter, or when the depleted shuttle is again 45 picked to the changing side of the loom. The detectors may therefore be conveniently located one above and the other below the boxes and the detection accomplished by box shifting without restricting the time of operation 50 of the knock-off devices which stop the lay.

From the foregoing it will be seen that I have provided an electric control circuit 55 which is normally open but is closeable at two points, one of which is determined by the condition of the weft and is effective only at exhaustion, and the other of which is closeable periodically. There is an interval of time between the closing of the circuit at these two points, this interval being sufficiently long to permit the actuator to pass the notch of the latch 39 on its working or knock-off stroke before the circuit is closed 60 at its second point. The relation of the parts is such that the interval will afford time for

all adjustments which are likely to arise in connection with the actuator and brake mechanism. The shuttle which is moving to inactive position gives indication of weft exhaustion, but this indication is not effective 70 to bring about a change in the loom operation until the shuttle is again active due to the timing of the parts described. When a previously raised inactive exhausted shuttle moves down through the position shown in 75 Fig. 5 toward the position suggested by the arrow in Fig. 6, the parts will be so related that the loom will be stopped as the lay reaches back center on the pick accompanying restoration of the depleted shuttle into 80 action.

Having thus described my invention it will be seen that changes and modifications may be made therein by those skilled in the art without departing from the spirit and scope 85 of the invention and I do not wish to be limited to the details herein disclosed, but what I claim is:

1. In weft detecting mechanism for looms having shuttle boxes which shift every other pick of the loom, an electrical weft detector for each box rendered operative by box shifting to detect weft in the corresponding shuttle when the same moves to inactive position, an actuator having a regular working stroke 90 every second pick of the loom, a member to be engaged by the actuator on a working stroke to stop the loom and initiate weft replenishment, a normally open switch, regularly acting means to close the switch after 95 the actuator has passed the member on a working stroke, an electro-magnetic device to control the member and tend to move the same into operative relation with the actuator, and an electric circuit including the device, switch and a detector and dependent upon closure of the switch to energize the 100 device. *

2. In weft detecting mechanism for looms having shuttle boxes which shift every other pick of the loom, a weft detector for each box effective to detect weft in the corresponding shuttle when the latter is moved to inactive position, an actuator having a regularly recurring working stroke every alternate pick 110 of the loom, a member to be engaged by the actuator on a working stroke and movable thereby to effect a change in loom operation, and a regularly moving element effective at a given point in the cycle of the loom after 115 the actuator passes the member on a working stroke to coat with the detector and cause movement of the member toward the path of movement of the actuator.

3. In weft detecting mechanism for a loom having shuttle boxes which shift every alternate pick of the loom and a lay movable back and forth, a detector for each shuttle box rendered operative by shifting movement of the boxes, each detector operative to detect 120 125 130

the condition of weft in the corresponding shuttle during the latter part of the shifting movement of the boxes which renders said shuttle inactive, a regularly moving actuator having a working stroke occurring on the backward movement of the lay, a member to be operatively related to the actuator and movable by the latter on a working stroke thereof to effect a change in loom operation, and an element normally ineffective to co-act with the detector but effective at a given point in the cycle of the loom after the actuator passes the member on a working stroke to coact with the detector and move the element toward the path of movement of the actuator when the detector indicates weft exhaustion.

4. In weft detecting mechanism for a loom having shuttle boxes which shift on alternate picks of the loom to render one of the shuttles inactive and the other shuttle active, an electric detector for each shuttle to coact with the shuttle moving to inactive position during the latter part of the shifting movement of the boxes, an actuator having a working stroke occurring regularly on alternate beats of the loom, a latch capable of coaction with the actuator to effect a change in loom operation, but normally out of the path of movement of the latter, an electro-magnetic device to move the latch toward the path of movement of the actuator, a timing switch normally open but closing on alternate beats of the lay after the actuator has passed the latch, and an electric circuit including the timing switch and the electro-magnetic device and a weft detector, said circuit dependent upon the closing of the timing switch to energize the electro-magnetic device, the actuator being rendered thereby effective on its next working stroke to engage the latch, said actuator capable of engaging the member at any one of a plurality of points in the cycle of the loom prior to the closing of said switch.

5. In weft detecting mechanism for a loom operating with shifting shuttle boxes each of which is active for but two picks at a time, an actuator having a regularly working stroke every other pick of the loom at a given time, an electro-magnetic device, an element controlled by the latter and movable thereby when energized into the path of movement of the actuator to be moved by the latter on the working stroke to effect a change in loom operation, an electric weft detector for each box effective to indicate exhaustion when the corresponding shuttle is depleted and in inactive position, and a normally open switch closing at regular intervals, the actuator moving beyond a position in its working stroke where it can be operatively related to the member before the switch is closed, and an electric circuit including the switch and electro-magnetic device and detector, said circuit dependent for closure and effectiveness to energize the device upon indication of weft exhaustion by the detector.

6. In weft detecting mechanism for a loom

having shuttle boxes which shift on alternate picks of the loom to render one of the shuttles inactive and the other shuttle active, an electric detector for each shuttle, each detector to coact with the corresponding shuttle when moving to inactive position during the latter part of the shifting movement of the boxes, an actuator having a working stroke occurring regularly on alternate beats of the loom, a latch capable of coaction with the actuator but normally out of the path of movement of the latter, an electro-magnetic device to move the latch toward the path of movement of the actuator, a timing switch normally open but closing on alternate beats of the lay after the actuator has passed the latch, and an electric circuit including the timing switch and the electro-magnetic device and a weft detector, said circuit dependent upon the closing of the timing switch to energize the electro-magnetic device, the actuator being rendered thereby effective on its next working stroke to engage the latch, said actuator capable of engaging the member at any one of a plurality of points in the cycle of the loom prior to the closing of said switch.

7. In a loom having a lay movable back and forth and provided with shifting shuttle boxes each in active position for but two picks at a time, the boxes shifting when the lay is in forward position, an electric weft detector brought into detecting relation with a box in inactive position by shifting of the boxes, an actuator having a working stroke during the pick when the boxes shift and operable through a range of time terminating when the lay reaches rearmost position following a box shift, an element normally out of the path of the actuator and movable by the latter to effect a change in the operation of the loom, an electro-magnetic device to move the element into the path of the actuator, a switch closable after the actuator has passed the element on a working stroke and during a range of time extending to the next shifting of the boxes, and a circuit including the switch and device and closable by a detector indicating weft exhaustion.

8. In a loom having a lay movable back and forth and provided with shifting shuttle boxes each in active position for but two picks at a time, the boxes shifting when the lay is in forward position, an electric weft detector brought into detecting relation with a box in inactive position by shifting of the boxes, an actuator having a working stroke during the pick when the boxes shift and operable through a range of time terminating when the lay reaches rearmost position following a box shift, an element normally out of the path of the actuator and movable by the latter to effect a change in the operation of the loom, an electro-magnetic device to move the element into the path of the actuator, a

switch closable between the time the actuator passes the element on a working stroke and the next shifting of the boxes, and a circuit including the switch and device and closable by a detector indicating weft exhaustion.

9. In weft detecting mechanism for a loom having a lay movable back and forth and having shifting shuttle boxes each of which is active for two picks and then inactive for two picks, an electrical weft detector to have detecting relation with a shuttle box moving to inactive position on a backward stroke of the lay, an element movable to effect a change in the operation of the loom, an actuator having a regular working stroke on box shifting picks of the loom and normally out of engagement with the element, a switch to be closed after the actuator has passed the element on a working stroke and opened before the actuator reaches the element on the succeeding working stroke, an electro-magnetic device to be in series with the switch and the detector when indicating weft exhaustion and effective to cause coaction between the actuator and the element, and means defining a shunt circuit to hold the electro-magnetic device energized when the switch opens.

10. In weft detecting mechanism for a loom having a lay movable back and forth and having shifting shuttle boxes each of which is active for two picks and then inactive for two picks, an electric detector rendered effective by shifting of the boxes to detect weft in the shuttle moving to inactive position on a backward stroke of the lay, a regularly moving actuator having a working stroke during the backward movement of each pick of the loom on which box shifting occurs, a switch to be closed at a point in the operation of the loom subsequent to the working stroke of the actuator, the switch remaining closed during part of the time that the detector is in detecting relation with the weft, the switch opening prior to completion of the next shifting of the boxes, electro-magnetic means to be actuated when the switch is closed and the detector indicates weft exhaustion and effective to cause the actuator to produce a change in the operation of the loom, and means to maintain the electro-magnetic device energized between the time the switch opens and the actuator has its next working stroke.

55 In testimony whereof I have hereunto affixed my signature.

LEWIS S. VOSE.
